MOPPING APPARATUS

Duane C. Wolfer, Vanport City, Oreg., assignor of
one-half to E. S. Hokanson, McMinnville, Oreg.

Application September 3, 1946, Serial No. 694,613

1 Claim. (Cl. 15—260)

1

The object of this invention is to provide a mop bucket and portable support therefor which serves to hold a mop in wringing position, which mop and bucket, however, may be easily and readily detachable for use.

A further object of my invention is to provide a mop having an absorbent applicator secured thereto, the handle for said mop having a notched engagement with a pressure applying device for compressing said absorbent applicator and expressing the dirty water therefrom.

A further and incidental object of my invention is to provide a wheel-mounted support for said bucket and mop, which support may be easily and quickly engaged by said mop to compress the water absorptive head and express the water therefrom into a bucket.

Further and other details of my invention are hereinafter described with reference to the accompanying drawings, in which:

Fig. 1 is a perspective view of a perforated mop-supported ledge, which may releasably be held in a bucket;

Fig. 2 is a foreshortened side elevation of a mop embodying my invention;

Fig. 3 is a sectional view taken on the line 3—3 in Fig. 2 through the head of said mop, showing the manner in which a sponge rubber applicator may be secured to the handle of said mop; and

Fig. 4 is a perspective view of a mop bucket carried by a wheel-supported carrier with a mop arranged therein for engagement by a portion of the carrier to express water from the head of said mop, a portion of the handle of said mop being shown broken away.

My invention is directed to a mop 1, comprising a head 2, to which is releasably attached a sponge rubber applicator 3. Said applicator has a recess formed upon one surface bounded by an upwardly and inwardly turned skirt, which encircles and overlies the mop head so that it may be firmly secured thereto but may also be easily detached by distending said skirt so that it does not engage said head. That is, the skirt is made of resilient rubber which is flexible and resilient. This permits said skirt to hold the applicator secured to the head but permits its ready detachment. Said head has a pair of upstanding ears 5 secured thereto, and the socket 6 for the mop handle 7 is pivotally mounted between said ears upon a shaft 8. A pair of detents 9, carried by one of the ears, is spring-pressed into an aperture (not shown) in the handle to hold it at a desired angular position with respect to the head.

Said socket is provided with a recess 10, which slopes downwardly and inwardly and is adapted to receive and hold the overlying portion of the bail 11 of the bucket support 12. Said bucket

2

support preferably comprises a triangular frame 13, supported by caster wheels 14, preferably arranged at the three corners thereof. A V-shaped foot lever 15 is pivotally supported in the free ends upon pivots 16 at the point where an upstanding arm 17 joins said frame 13. A tension spring 18, connected between said foot lever and said arm at each side, tends to hold lever upwardly in the position shown in Fig. 4.

10 The bail 11 straddles a mop bucket 19, carried by the bucket support 12, the ends of said bail being secured at the opposite sides of said bucket on pivot connections made with the foot lever 15. Laterally projecting ears 17^a are arranged at the end of the arms and have apertures arranged therein through which the arms of the bail 11 pass and with which they slidably engage. When the mop is arranged as is shown in Fig. 4, it is supported by a perforated shelf 21 arranged slightly below the margin or upper edge 19^b of the bucket, but well above the bottom thereof. The mop bucket preferably is provided with an imperforate partition 19^a, and said shelf overlies a portion of said bucket at one side of the partition. Said shelf preferably is supported by three hooks 21^a, which engage the marginal edge 19^b of the bucket and depend into said bucket, lying closely alongside the inside surface thereof. Said shelf conforms in its outline to 20 that of the inner surface of the bucket, and thus fits quite snugly within said bucket and at one side of the partition 19^a thereof.

The bail 11 is bent laterally so as to permit the mop handle 7 to be arranged vertically, and thus 25 when the foot lever 15 is depressed, the bail exerts a squeezing force through its engagement with the handle to press the sponge rubber applicator against the perforated shelf 21 to express the dirty water from said sponge rubber.

30 When foot pressure is released, the tension spring 18 lifts the foot lever, and the mop may be removed by disengaging the recess 10 from the bail 11. The bucket 19 also can easily be removed from its support 12 when the mop is not in place 35 merely by sliding it out from under the bail. The partitioned bucket permits clean water to be carried in one-half thereof and collects dirty water expressed from the sponge rubber, at the other side of the partition. For convenience, it is preferred that the bail 11 of the mop bucket be arranged away from the point of the foot lever for 40 convenience in inserting and removing the mop bucket from its support 12. The bucket is seated in an open-mouthed frame 12^a which closely encircles it but from which it may easily be lifted.

45 It is preferred that the skirt 4 of the sponge rubber applicator be made of tougher and denser rubber so that it will resist strains which would tend to disengage the applicator from the head 2 50 of the mop. In other words, it is not necessary 55 to provide a recess 10 in the head 2 of the mop to receive the bail 11 of the bucket support 12. The bucket is seated in an open-mouthed frame 12^a which closely encircles it but from which it may easily be lifted.

that said skirt be made of sponge rubber, because it plays no part in the mopping operation. It is essential, however, that said skirt provide a secure grip to the head to prevent inadvertent disengagement of said parts.

Said mopping apparatus is used as follows: The mop, free of the bucket and its support, is depressed into the clean water at the right-hand side of the partition, as is shown in Fig. 4. When the mop is to be cleaned, it is arranged with the handle upright and with the recess in engagement with the bail 11, as is shown in Fig. 4. The V-shaped lever is then pushed down by foot action applied to the apex thereof, which is the left-hand portion shown in Fig. 4, until the bail compresses the sponge rubber applicator to the desired degree to express the dirty water therefrom. The foot lever is then released and the mop which is thus wrung out may again be released from the bail and dipped in the clean water to form continuing mopping. This is continued until the water in the bucket is dirty. Then the bucket can be removed by disengaging it from its support 12 and a fresh supply may be provided. The arrangement of the bucket with relation to its support tends to prevent overturning when the foot lever is pressed down. If the applicator becomes worn or distorted by having the cellular structure broken down, a new applicator may be easily and quickly equipped to the head merely by disengaging the skirt from the head, and a new applicator can be put into place by the reverse action. Also, if the length of travel of the bail is insufficient to squeeze the applicator, additional pressure may be provided by prying by the use of the mop handle.

I claim:

A floor mop squeezing apparatus, comprising a wheel mounted support carrying an open-mouthed bucket supporting frame, an elongated V-shaped lever pivotally connected at the ends thereof to said wheel mounted support, said lever straddling said bucket frame and being fulcrumed upon said wheel mounted support in overlying position for manual depression toward said support, an integral U-shaped bail member pivotally joined at the ends thereof to said lever for depression therewith, a pair of spaced guide members carried by said wheel mounted support and

extending upwardly therefrom, each said guide member terminating in an aperture through which one leg of said U-shaped bail member slidably is threaded to guide the bail during said manual depression, a tension spring means fixed to each said guide and to the side of said lever companion thereto to bias said lever against said manual depression, a bucket removably seated in said open-mouthed frame and carrying a mop support with a mop seated therein, said mop having a mop head lying below the plane of the top of said bucket and pivotally joined to one end of a mop handle, and a cupped recess in said mop handle intermediate the ends thereof, said U-shaped bail member overlying said mop head and being complementary to and removably seated in said recess to apply squeezing force to said mop head during said manual depression against the force of said spring bias.
